(57) **CLAIM**

The ornamental design for a circuit controller, as shown and described.

DESCRIPTION

FIG. 1 is a perspective view of the circuit controller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an another perspective view thereof; and,

FIG. 9 is a reference view showing the circuit controller being in using status.

The broken line portion of the figure drawings is included to show portions of the circuit controller that form no part of the claimed design.

1 Claim, 9 Drawing Sheets

FIG. 5

FIG. 9
